UNITED STATES PATENT OFFICE.

THOMAS J. GILL, OF STOCKTON, CALIFORNIA.

SIGN.

1,056,165.

Specification of Letters Patent. Patented Mar. 18, 1913.

Application filed September 23, 1912. Serial No. 721,654.

To all whom it may concern:

Be it known that I, THOMAS J. GILL, a citizen of the United States, residing at Stockton, in the county of San Joaquin and State of California, have invented certain new and useful Improvements in Signs, of which the following is a specification.

This invention relates to improvements in signs, and especially illuminated signs; and 10 the object of the invention is to provide a sign of this kind which shall be simple and inexpensive in construction, and which can be read by persons approaching from either side thereof.

15 With these objects in view, the invention consists in a novel combination and arrangement of parts to be hereinafter described and claimed.

In the accompanying drawing forming a 20 part of this specification—Figure 1 is a plan view of the sign, partly in section; Fig. 2 is a cross-section on the line 2—2 of Fig. 1; Fig. 3 is a front elevation of the sign, and Fig. 4 is a longitudinal section on the line 25 4—4 of Figs. 1 and 2.

As will be seen in the drawing, the main body of the sign is an elongated, rectangular inclosure formed of front and rear walls 7, and a top 7^a, said parts being fastened together with spacers 11 on each end, on the top by angles 13; and on the bottom by angles 9 and supports 2 for the lamps 1. This makes a light and strong construction for the main body of the sign. Any suitable material may be used for the parts 7 and 7^a.

The walls 7 are stenciled, as indicated at 15, to form the letters of the sign, in view of which a double sign is had, the letters being displayed in front and at the rear. The 20 openings forming the letters are covered by a wire screen 10 placed against the inner surface of the walls 7, the same being held by strips 10^a fastened to said walls on the inner surface thereof, at the top and bottom and outside the letters.

The lamp supports 2 extend transversely between the walls 7, and rest on the horizontal flanges of the angles 9, the vertical flanges thereof fitting between the bottom strips 10^a

and the ends of the lamp supports. Three 50 lamp supports are shown, one being located midway between the ends of the sign, and one at each end. The intermediate support carries a lamp on each side, and the end supports carry each one lamp. A greater 55 number of supports and lamps may be provided for larger signs. The lamps 1 are secured to the supports 2 midway between the front and rear walls 7, in any suitable manner, and they are all set horizontally, thereby 60 presenting a larger area of lighting surface.

In the inclosure, at the top thereof, is mounted a concavo-convex reflector 14. From the concave side of the reflector depends a partition 8 which extends through- 65 the entire length of the inclosure, midway between the front and rear walls 7 thereof, and terminates a short distance above the lamps 1. The light from the lamps strikes the partition, which latter 70 throws the light out through the letter open- 75 ings 15 in the front and rear walls 7. The light which is cast on the reflector 14 is partly cast on the partition, as well as reflected through the bottom of the inclosure to the side-walk, said bottom being open.

At 3 are indicated porcelain insulators which are mounted on the walls 7 where the feed wires 4 connect with the feed wires 5 and 6 of the lamps 1. 80

A sign constructed as herein described is simple and cheap, and makes an attractive display. The wire screen 10 sharpens the outlines of the letters, and also keeps flies, birds, insects and foreign materials out of 85 the inclosure. The light is equally distributed over both faces of the sign, which are thus brilliantly illuminated. The interior mechanism is fully protected from wind and rain. 90

The preferred embodiment of the invention has been shown but it will be understood that various minor changes in the structural details may be made without a departure from the spirit and scope of the invention as hereinafter claimed. 95

I claim:

A sign comprising an inclosure having

opposite sides which are perforated to form the letters of the sign, lights in the bottom portion of the inclosure, a concavo-convex reflector in the inclosure above the lights, 5 and a partition depending from the middle line of the concave side of the reflector intermediate the perforated sides of the inclosure.

In testimony whereof I affix my signature in presence of two witnesses:

THOMAS J. GILL.
